US0D1085958S

(12) **United States Design Patent** (10) Patent No.: **US D1,085,958 S**
(45) Date of Patent: ** Jul. 29, 2025

(54) **GRILLE ELEMENT**(71) Applicant: **Oshkosh Corporation**, Oshkosh, WI (US)(72) Inventor: **Jesse Gander**, Larsen, WI (US)(73) Assignee: **OSHKOSH CORPORATION**, Oshkosh, WI (US)(**) Term: **15 Years**(21) Appl. No.: **29/982,694**(22) Filed: **Jan. 7, 2025****Related U.S. Application Data**

(63) Continuation of application No. 29/846,774, filed on Jul. 19, 2022, now Pat. No. 1,064,940, which is a continuation of application No. 29/802,904, filed on Aug. 9, 2021, now Pat. No. Des. 966,958, which is a continuation of application No. 29/750,416, filed on Sep. 14, 2020, now Pat. No. Des. 929,913, which is a continuation of application No. 29/729,772, filed on Mar. 30, 2020, now Pat. No. Des. 898,632, which is a continuation of application No. 29/706,526, filed on Sep. 20, 2019, now Pat. No. Des. 892,002, which is a continuation of application No. 29/691,172, filed on May 14, 2019, now Pat. No. Des. 863,144, which is a continuation of application No. 29/621,906, filed on Oct. 12, 2017, now Pat. No. 856,860, which is a continuation of application No. 14/612,100, filed on Feb. 2, 2015, now Pat. No. 9,829,282, which is a continuation of application No. 13/629,009, filed on Sep. 27, 2012, now Pat. No. 8,943,946, said application No. 29/621,906 is a continuation of application No. 15/599,174, filed on May 18, 2017, now Pat. No. 10,434,995, which is a continuation of application No. 14/724,279, filed on May 28, 2015, now Pat. No. 9,656,640, which is a continuation of application No. 13/841,686, filed on Mar. 15, 2013, now Pat. No. 9,045,014.
